UNITED STATES PATENT OFFICE.

MATTEO DE CESARE, OF NEWARK, NEW JERSEY, ASSIGNOR, BY MESNE ASSIGNMENTS,
TO VOICES INCORPORATED, A CORPORATION OF DELAWARE.

SOUND-REPRODUCING DEVICE.

Application filed March 21, 1923, Serial No. 626,615. Renewed February 26, 1928.

This invention relates to sound reproducing devices and more particularly to a novel and improved mechanical device that is positioned within the body of a doll or toy so that when the latter is moved or turned, a crying sound will be reproduced.

The main object of my invention is the provision of a mechanical sound reproducing device which is extremely simple in construction, easily assembled, highly efficient in operation and use, practical, durable, and otherwise adapted for easy installation in various types of mechanical toys and dolls.

Further and more specific objects, features and advantages will more clearly appear from the detail description given below taken in connection with the accompanying sheet of drawings, showing a preferred embodiment of the invention and forming a part of this specification, and wherein;

Figure 1 is a vertical section through the device showing the bellows in its extended position.

Figure 2 is a vertical section through the device when the same is inverted.

Figure 3 is a plan view of the weighted element showing the relative arrangement of the reed and cup.

Referring now to the drawings wherein like reference characters designate corresponding parts throughout the several views, 5 designates the body or tubular casing which encloses the sound reproducing device and is of such form as readily adapts itself for easily securing in the body of a toy, such as a doll. Tubular bellows 6, preferably of rubber and of a length so that the top edge 7 extends over the top end of the casing 5, is secured thereto by the flanged cover 8 overlying the edge of the bellows and the top of the casing above referred to so that the cap 8 closes one end of the bellows as well as one end of the casing. A weighted element designated in its entirety by numeral 10 is composed of a circular disc-shaped weight freely tiltable in all directions in the casing. That is, the weight 10 is not only capable of falling back and forth in the casing as the position of the device is changed, but the weight may assume different angles with respect to the casing as it moves from one position to another in the casing. The weight 10 is secured by a band or ring 11 to the bottom end of the bellows 6 so as to trap the air within the bellows when

the same is extended to the position shown by Figure 1 of the drawings. All parts of the weighty head 10 are thus movable by gravity back and forth in the casing in a direction parallel to the axis of the casing. 60 The weighted element 10 is thus freely tiltable in all directions against the sides of the casing. The weighted head is provided with a recess or aperture therethrough to receive a cylindrical cup 12 preferably at one side thereof, said cup 12 having a recess in the side thereof and below the weighted element 10 to receive a horizontally extending tube 13 which forms a passage so as to communicate with the interior of the cup and the 70 bellows. A reed pipe having a reed 14, extending within the tube 13, controls the entry and passage of air from the exterior of the device and the casing 5. A guard or protector 14^a, open at the end is positioned 75 over the reed to protect the same. It will be seen that the sounding reed carried by the weight extends substantially parallel to the opposite faces of the weight and means are provided extending about the reed to 80 protect the same and forming a passageway also extending substantially parallel to the opposite faces of the weight and within which passageway the reed is located, the reed being in communication with the aperture or opening through the weight whereby the air entering or leaving the bellows passes the reed, the air being adapted to pass from the reed to the opposite side of the weight as the bellows is operated. The bottom of said casing is preferably closed by a meshed piece of fabric 15 having apertures therethrough which is secured by a flanged ring or apertured cap 16 to the bottom. 85

It will thus be seen that when the bellows 90 is being expanded, the air will pass into the bellows through the reed pipe in which the reed 14 is positioned, consequently, producing the crying sound as desired. That is, the reed is caused to sound when the bellows 95 is expanded or distended by movement of the weighty head away from the fixed head 8. Whenever, the device is inverted, the weight 10 will tend to collapse the bellows, as shown by Figure 2, in which instance the air will be forced out through the passage and reed pipe. The particular sound desired can be regulated and controlled 100 by the size of the air passage and the cup utilized as well as the particular reed but the 110

operation primarily depends upon the movement of the weighted element 10, it being of course understood that the length of the sound emitted, will vary with the time that it takes to completely expand the bellows. I find it particularly advantageous to arrange and position the sound reed so that it will sound upon expansion or elongation of the bellows (as distinguished from compression 10 of the bellows) in this type of device where the weighty head and all parts thereof are movable back and forth in the casing in a direction parallel to the axis of the casing and the head is freely tilttable in the casing.

15 While I have not shown any particular means for securing or fastening the sound reproducing device in the doll or toy as the case may be, in actual practice, the device is positioned so that when the roll is turned, 20 the weight 10 will fall by gravity with the result that the sound will be produced.

While I have illustrated and described my invention with some degree of particularity, I realize that various alterations therein may 25 be made. I therefore reserve the right and privilege of changing the form of the details of construction or otherwise altering the arrangement of the correlated parts without departing from the spirit of the invention 30 or the scope of the appended claims.

Having thus described my invention, what I claim as new and desire to secure by United States Letters Patent is:—

1. A sounding device having in combination 35 a tubular casing, a tubular bellows member therein, a cap closing one end of the bellows member and one end of the casing and securing said end of the bellows member to the casing, an apertured cap on the other 40 end of the casing, a circular disc shaped weight, said weight being freely tilttable in all directions in the casing, a circular metal clamping member and clamping the other end of the bellows member to the periphery 45 of said circular weight, whereby the weight may fall back and forth in the casing as the position of the device is changed to alternately compress and distend the bellows member and force air out and in thereof, and 50 a sounding reed carried by the weight and extending substantially parallel to the opposite faces of the weight, said weight having means extending about the reed to protect the same and forming a passageway extending 55 substantially parallel to the opposite faces of the weight and within which passageway the reed is located, said weight having an opening therethrough, through which opening air is adapted to pass from the reed to the opposite side of the weight to operate the reed as the bellows member is operated.

2. A sounding device having in combination 60 a tubular casing, a tubular bellows member therein, means secured to the casing ad-

jacent one end thereof and closing one end of the bellows member, means having apertures therethrough closing the other end of the casing, a circular disc shaped weight, said weight being freely tilttable in all directions in the 70 casing, means clamping the other end of the bellows member to the periphery of said circular weight whereby the weight may fall back and forth in the casing as the position of the device is changed, to alternately compress and distend the bellows member and force air out and in thereof, and a sounding reed carried by the weight and extending substantially parallel to the opposite faces of the weight, said weight having means extending 80 about the reed to protect the same and forming a passageway extending substantially parallel to the opposite faces of the weight and within which passageway the reed is located, said weight having an opening therethrough through which opening air is adapted to pass from the reed to the opposite side of the weight to operate the reed as the bellows member is operated.

3. A sounding device having in combination 85 a cylindrical casing having two heads therein, one fixed with respect to the casing and the other a weighty head movable back and forth in the casing toward and from the fixed head by gravity, and freely tilttable 90 in all directions in the casing, a tubular bellows connecting said heads whereby the bellows will be compressed when the movable head moves toward the fixed head and distended when the movable head moves away 95 from the fixed head, and a reed pipe carried by one of said heads, said reed pipe being arranged so that it will be operated by air passing into the bellows and will sound when the bellows is expanded.

4. A sounding device having in combination 100 a tubular bellows, a circular head closing one end of the bellows, a relatively movable circular head closing the other end of the bellows, said last mentioned head being 105 weighted whereby it will move by gravity back and forth to compress and distend the bellows, a reed pipe carried by the weighty head, said weighty head being freely tilttable against the sides of the casing, said reed pipe 110 being arranged so that it will be operated by air passing into the bellows and will sound when the bellows are expanded.

5. A sounding device having in combination 115 a tubular casing, a tubular bellows in 120 said casing, a head closing one end of the bellows and fixed with respect to the casing, a weighted head closing the other end of the bellows, all parts of which head are movable by gravity back and forth in the casing in a 125 direction parallel to the axis of the casing, and said weighted head being freely tilttable against the sides of the casing, one of said heads, having an aperture therethrough, a reed pipe associated with said aperture, said 130

- reed pipe having a sound reed so positioned that the reed will sound by reason of air passing therethrough into the bellows when the bellows is expanded by movement of the weighted head away from said fixed head.
6. A sounding device having in combination a tubular casing, a tubular bellows in said casing, a head closing one end of the bellows and fixed with respect to the casing, a weighted head closing the other end of the bellows, all parts of which head are movable by gravity back and forth in the casing in a direction parallel to the axis of the casing, said weighted head being freely tiltable in all directions in the casing, one of said heads having an aperture therethrough, a reed pipe associated with said aperture, said reed pipe having a sound reed so positioned that the reed will sound by reason of air passing therethrough into the bellows when the bellows is expanded by movement of the weighted head away from said fixed head, 15 20 an apertured cap for the end of the casing opposite the fixed head.
10. A sounding device having in combination a tubular casing, a tubular bellows in said casing, a head closing one end of the bellows and fixed with respect to the casing, a weighted head closing the other end of the bellows, all parts of which head are movable by gravity back and forth in the casing in a direction parallel to the axis of the casing, In testimony whereof I affix my signature.

MATTEO DE CESARE. [L.S.]
